UNITED STATES PATENT OFFICE

HARRY F. WANAMAKER, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA

AUTOMATIC HOSIERY DRIER TABLE LEVELING MECHANISM

Application filed March 18, 1932. Serial No. 599,840.

This invention relates to apparatus for handling articles of manufacture composed of flaccid materials, such as stockings, and more particularly to a receiving table of the general character disclosed in U. S. Letters Patent No. 1,189,064 when employed in conjunction with an automatic hosiery drier wherein the stockings are automatically stripped from the forms after drying and 10 laid successively upon a receiving table, as disclosed in United States Letters Patent No. 1,126,619.

The receiving table disclosed in the first mentioned patent is composed of a series of 15 stationary slats respectively alternating with a series of relatively movable slats, the latter being adapted to be raised above the stationary slats to lift the articles supported thereby to a plane above the top 20 edges of the stationary slats, the movable slats then being moved longitudinally of and with respect to the stationary slats to transport the lifted articles longitudinally of the stationary slats while the movable slats are 25 maintained in a raised position, the movable slats being subsequently lowered to deposit the articles on the stationary slats and continuing to move to a position below the stationary slats wherein the movable slats are 30 moved longitudinally in an opposite direction to the starting position for a repeat of the cycle of operation.

The receiving table is provided with piling mechanism which comprises a series of bars 35 respectively overlying the stationary slats at one end of the table. These piling bars are primarily elevated above both the stationary and relatively movable slats of the table and as the stockings are disposed one after another on the elevated piling bars these bars are lowered step by step until they come to rest on, or assume positions immediately adjacent and above, the stationary slats, after 40 a predetermined number of stockings have been piled in superposed relation upon the piling bars.

When the piling bars move to their maximum low position the mechanism controlling the operation of the movable slats of the 50 table, as above noted, is brought into action

to move the pile of stockings off the piling bars to a position spaced from the piling bars in a direction longitudinally of the table, after which the piling bars are raised automatically to their primary or maximum high 55 position, above referred to for starting another pile.

With the piling bars in the elevated position openings are left between the bars, said openings being substantially equal to the respective widths of the movable slats, and as the stockings are piled on the spaced piling bars they sag between the bars into the said spaces, consequently, the stockings, and particularly the stockings at and adjacent the 60 bottom of the pile, assume a more or less undulated form. As a result of these undulations in the lowermost stockings, when the piling bars are lowered and the movable slats raised to lift the pile of stockings from the 65 piling bars the movable slats engage the undulated portions of the lowermost stockings, causing the stockings to become more or less wrinkled.

The object of the present invention is to 75 provide a table whereby the stockings will be piled, and the piles transported in the same general manner as above noted, but, wherein the piling bars are eliminated and the movable and stationary slats are maintained at all times in substantially coincident 80 planes transversely of the table, at the receiving end of the table, the stockings being piled in superposed relation on the coinciding 85 ends of the two series of slats, and due to the level or coincident relation existing between the stationary and movable slats no undulations are formed in the stockings, as by sagging in the manner above noted.

The coincidently arranged piling ends of 90 the stationary and movable slats are lowered step by step as a unit during the piling operation, and by which the two series of slats are brought into a substantially leveled 95 or coinciding relation with respect to each other throughout their entire lengths respectively, when a predetermined number of stockings are piled on the receiving end of the table, the pile being subsequently transported along the table by cooperative move- 100

ment of the one series of slats with respect to the other series of slats, in the manner above noted.

The construction and operation of the mechanism forming the subject of the present invention will be fully disclosed hereinafter, reference being had to the accompanying drawings, of which:

Fig. 1 is a front elevation showing the piling or receiving end of the table in the maximum high position;

Fig. 2 is a plan view of the mechanism shown in Fig. 1;

Fig. 3 is an end view;

Fig. 4 is a diagrammatic view showing the stationary and movable slats in their completely leveled position at the completion of the formation of a pile of stockings at the receiving end of the table;

Fig. 5 illustrates the movable slats as having raised the pile of stockings for transportation along the table;

Fig. 6 shows the movable slats having been moved longitudinally with respect to the stationary slats with the pile of stockings thereon;

Fig. 7 illustrates the movable slats as having been lowered to deposit the pile of stockings on the stationary slats at a position longitudinally removed from the piling position on the table.

As shown in the drawings, the device comprises side frame members 1 and 2 at one end of the table connected by a transversely extending beam 3, and a transversely extending end frame 4 at the opposite end of the table. Supported by the frame members 3 and 4 are longitudinally extending stationary frame beams 5, 5, the ends of the said beams overlying the transverse frame member 3 being supported from said frame member 3 by means of vertically extending brackets 6, 6 respectively, while the opposite ends of said beams are secured directly to the end frame 4.

Secured to and extending above the end frame 4 is a relatively flexible plate 7 to which one end of each of a series of stationary slats 8, 8 is secured, the said plate functioning as a common fulcrum for the entire series of stationary slats 8, for purposes hereinafter set forth. The opposite end of each stationary slats is secured to a plate 9 which is supported by a pair of vertically extending rods 10 passing through bearings 11 secured to the ends of the beams 5, 5 respectively. The opposite ends of the rods 10 are pivotally attached to the outer ends of levers 12, 12 which are secured to a rock shaft 13 that is rotatably supported in bearings 14 and 15 carried by the frame members 1 and 5 respectively. The shaft 13 is provided with a lever 16 having a cam follower 17 operating in a cam groove 18 formed on one face of a wheel 19.

The wheel 19 is rotatably supported on a stud 19a carried by and projecting laterally from the frame member 1. The periphery of the wheel 19 is provided with a series of teeth 21 with which cooperates a roller 20 carried by a crank arm or disc 22 secured to the main operating shaft 23 of the machine, the disc 22, the roller 20 and the teeth 21 of the wheel 19 providing a Geneva movement which controls the position of the cam path 18 with respect to the cam follower 17 and thereby lowers the plate 9 and the stationary slats 8, 8, step by step as each stocking is laid on the coinciding ends of the fixed slats 8 and the movable slats 25 adjacent the plate 9, the shaft 23 receiving one complete rotation for each stocking placed on the table and the number of teeth on the wheel 19 governing the number of stockings in each pile.

The relatively movable slats 25 are disposed in alternate relation to the stationary slats 8, the slats 25 being respectively disposed in the spaces between the stationary slats. The movable slats 25, 25 are supported adjacent the opposite ends thereof by brackets 26, 26 which are respectively secured to transversely extending supporting members 27, 27. The transverse members 27, 27 are secured to longitudinally extending bars 28, 28 and together therewith constitute a supporting frame for the series of movable slats 25.

The frame members 28 are supported at their ends adjacent the end frame 4 on rollers 29, 29 which are rotatably mounted on the outer ends of levers 30, 30 secured to a transversely extending rock shaft 31 that is rotatably mounted in suitable bearings carried by the frame beams 5, 5. The rollers 29 function as a common fulcrum for the movable slats 25, 25.

The opposite ends of the frame members 28 are provided with rollers 32 which are adapted to ride on inclined rails 33, 33 carried by plates 34, 34 which are secured to the end plate 9 and project laterally therefrom in a direction longitudinally of the table beneath the stationary slats 8 and movable slats 25 thereof.

As shown in Figs. 1 and 2, the ends of the slats 8 and 25, adjacent the end plate 9, have their upper edges disposed in substantially the same plane, transversely of the table, eliminating any decided openings between any two slats, while the movable slats 25 are inclined with respect to the stationary slats in a direction longitudinally of the table, the opposite ends of the movable slats 25 being disposed in a plane somewhat below that of the top edges of the stationary slats 8, and inwardly disposed with respect to the fulcrum plate 7.

Rotatably mounted in bearings carried by the beams 5, 5 is a shaft 31a on which is se-

cured levers 30a provided with rotatably mounted rollers 29a.

Secured to the shafts 31 and 31a respectively are levers 35 and 35a which are operatively connected by a link 36 having a head 37 which encircles and cooperates with a cam 38 that is secured to a sleeve shaft 44, surrounding the shaft 23, for rocking the shafts 31, 31a at a predetermined time in exactly the same manner, whereby the rollers 29 and 29a are at all times maintained in the same horizontal plane with respect to each other.

As the wheel 19 is rotated step by step the ends of the slats 8 and 25, adjacent the end plate 9, are simultaneously lowered and maintained at all times in substantially the same plane during the lowering operation, the plate 7 at the opposite end of the slats 8 flexing sufficiently to permit the change in angle of inclination of the slats 8, resulting from the pivotal action of said slats, while the longitudinal frame members 28 supporting the ends of the movable slats 25 adjacent the plate 7 ride and pivot on the rollers 29 to accommodate the change in angle of inclination of the slats 25.

When lowered to the maximum extent the upper edges of the slats 8 and 25 are in substantially the same plane entirely throughout their lengths as illustrated in Fig. 4, and at which time the frame members 28 intermediate the opposite ends thereof come to rest on the rollers 30a.

At this time the mechanism for raising the movable slats relative to the stationary slats; for moving the movable slats longitudinally with respect to the stationary slats; for lowering the movable slats below the plane of the stationary slats; and for returning the movable and stationary slats to a starting position is brought into action.

The continuously rotating main shaft 23 is provided with a clutch element 40 which is rigidly secured to said shaft 23 and which, in the present instance, is provided with an opening 41 adapted to receive a pin 42 slidably mounted in a clutch element 43 secured to one end of the sleeve shaft 44 that surrounds the main shaft 23, as above noted, the clutch pin 42 being provided with a wedge member or head 45 that engages and up on one end of a laterally extending rod 46, for the purpose of pulling the clutch pin 42 out of the opening 41 in the constantly rotating clutch element 40, whereby the sleeve shaft 44 is brought to rest.

The clutch-controlling rod 46 in the present instance is provided with relatively spaced collars 47, 48 between which operates fork ends 49a, 49a of a lever 49 that is secured to the table-lowering shaft 13.

When the table-lowering shaft 13 has been rocked through the medium of the cam or counting wheel 19, to the extent wherein the table is in its lowermost and horizontally lev-

eled position, the upper ends 49a of the lever 49 engage the collar 47 and withdraws the end of the rod 46 from under the wedge-shaped head 45 of the clutch pin 42, whereby the clutch pin enters the opening 41 in the clutch element 40, locking the clutch elements 40 and 43 and consequently the shafts 23 and 44 together for rotation in unison.

The cam element 38 which is fixed to the sleeve shaft 44 is consequently rotated, thereby rocking the shafts 31, 31a and raising the rollers 29, 29a which raises the frame 28 and consequently the slats 25 to a position with their upper edges above the plane of the upper edges of the stationary slats 8 as illustrated in Fig. 5. The rollers 32 on the frame members 28 are lifted from the inclined rails 33 during this and the immediately following operations, the frame 28 and slats 25 being supported solely by the rollers 29, 29a whereby free longitudinal movement of the frame 28 and slats 25 in a horizontal plane is permitted.

Secured to the sleeve shaft 44 is a second cam 50 which cooperates with a housing 51 having a pivotal connection, as at 52, with a lever 53 secured to a shaft 54 that is rotatably mounted in the frame of the machine. The cam housing 51 is also pivotally connected at 55 to one end of a lever 56, the opposite end of which is freely rotatable on the shaft 31a.

Secured to the shaft 54 is a lever 57, the opposite end of which is pivotally connected as at 58 to one end of a link 59, the opposite end of said link being pivotally connected at 60 to a bearing or bracket 61 that is secured to one of the cross members 27 of the frame which supports the movable slats 25.

As the shaft 44 rotates and the cam 38 functions to raise the frame 28 and the slats 25, the housing 51 is raised by the cam 50, causing a rocking of the shaft 54 which, through the lever 57 and link 59, causes a longitudinal movement of the slats 25 toward the end plate 7 of the table, while the said slats are maintained in their elevated position above the stationary slats 8 by the rollers 29, 29a through the medium of the cam 38, whereby the slats 25 attain a position with their upper edges elevated above the upper edges of the stationary slats 8, as illustrated in Fig. 6.

Continued rotation of the shaft 44 lowers the frame 28 and the slats 25 carried thereby to a position below the stationary slats 8 as illustrated in Fig. 7, the frame 28 and slats 25 then moving in an opposite direction below the level of the upper edges of the stationary slats 8.

At this time the roller 20 engages another of the teeth 21 of the wheel 19 thereby rotating the cam 18 to a position wherein the cam follower 17 rides quickly from the low point of the cam 18 to the high point thereof,

which causes an elevation of the plate 9 and the receiving ends of the stationary slats 8 through a rocking of the shaft 13, as effected by the movement of the cam follower 17 from 5 the maximum low to the maximum high position in the cam 18.

The rocking of the shaft 13 as noted causes the ends 49a, 49a of the lever 49 to engage the collar 48 of the clutch-controlling rod 10 46, thereby projecting the above mentioned end of the rod into the path of the wedge head 45 of the clutch pin 42.

During this time the frame 28 and movable slats 25 are moving in a direction toward the 15 receiving end of the table, that is, toward the plate 9, and just prior to the engagement of the wedge head 45 of the clutch pin 42 with the controlling rod 46 the rollers 32 on the frame 28 engage the lower ends of the inclined rails 33 and ride up on the said inclined rails, thereby raising the receiving ends of the movable slats 25 into the position shown in Fig. 1, wherein the receiving ends of the movable slats 25 and the receiving 20 ends of the stationary slats 8 are in substantially the same plane transversely of the table, as shown in Fig. 3. The clutch pin 42 is finally withdrawn from the opening 41 in the continuously rotating clutch element 40, 25 thereby releasing the sleeve shaft 44 from the continuously rotating main shaft 23 while the table elements 8 and 25 are in the position noted, leaving the movable slats in the relation to the stationary slats as shown in 30 Fig. 1 for a repeat of the cycle of operation beginning with the lowering of the receiving end of the table including the stationary slats 8 and movable slats 25.

I claim:

40 1. A table for receiving flaccid articles transversely of and at one end thereof, said table comprising a series of longitudinally fixed slats, a series of longitudinally movable slats alternating respectively with the fixed 45 slats with the upper edges of the movable slats at the receiving end of the table in a plane substantially coinciding transversely of the table with the plane of the upper edges of the fixed slats, means for lowering the receiving end of the table including the coinciding ends of the two series of slats, and means for maintaining the said coinciding relation of the two series of slats during the said lowering thereof for smoothly supporting the 50 article.

2. A table for receiving flaccid articles transversely of and at one end thereof, said table comprising a series of longitudinally fixed slats, a series of longitudinally movable 60 slats alternating respectively with the fixed slats with the upper edges of the movable slats at the receiving end of the table in a plane substantially coinciding transversely of the table with the plane of the upper edges of the fixed slats, the upper edges

of one series of slats being inclined with respect to the upper edges of the other series of slats in a direction longitudinally of the table from the receiving end toward the opposite end thereof, a common fulcrum for the slats of one series at the said opposite end of the table, a common fulcrum for the slats of the other series disposed inwardly from the first said fulcrum, means for lowering the receiving end of the table including the coinciding ends of the two series of slats for leveling the two series of slats with the upper edges thereof in substantially coinciding planes throughout their respective lengths, and means for maintaining the said coinciding relation of the two series of slats during the said lowering thereof for smoothly supporting the article.

3. A table for receiving flaccid articles transversely of and at one end thereof, said table comprising a series of longitudinally fixed slats, a series of longitudinally movable slats alternating respectively with the fixed slats with the upper edges of the movable slats at the receiving end of the table in a plane substantially coinciding transversely of the table with the plane of the upper edges of the fixed slats, the upper edges of one series of slats being inclined with respect to the upper edges of the other series of slats in a direction longitudinally of the table from the receiving end toward the opposite end thereof, a common fulcrum for the slats of one series at the said opposite end of the table, a common fulcrum for the slats of the other series disposed inwardly from the first said fulcrum, means for lowering the receiving end of the table including the coinciding ends of the two series of slats for leveling the two series of slats with the upper edges thereof in substantially coinciding planes throughout their respective lengths, means for maintaining the said coinciding relation of the two series of slats during the said lowering thereof for smoothly supporting the article, and means for elevating and longitudinally moving the movable slats relative to the fixed slats to transport the article longitudinally of the table.

4. A table for receiving flaccid articles transversely of and at one end thereof, said table comprising a series of longitudinally fixed slats, a series of longitudinally movable slats alternating respectively with the fixed slats with the upper edges of the movable slats at the receiving end of the table in a plane substantially coinciding transversely of the table with the plane of the upper edges of the fixed slats, the upper edges of one series of slats being inclined with respect to the upper edges of the other series of slats in a direction longitudinally of the table from the receiving end toward the opposite end thereof, a common fulcrum for the slats of one series at the said opposite end of the

- table, a common fulcrum for the slats of the other series disposed inwardly from the first said fulcrum, means for lowering the receiving end of the table including the coinciding 5 ends of the two series of slats for leveling the two series of slats with the upper edges thereof in substantially coinciding planes throughout their respective lengths, means for maintaining the said coinciding relation 10 of the two series of slats during the said lowering thereof for smoothly supporting the article, means for elevating, longitudinally moving, and subsequently lowering the movable slats relative to the fixed slats to lift, 15 transport, and subsequently redeposit the article on the fixed slats in a position on the table relatively spaced from the receiving end of the table and for subsequently moving the movable slats in an opposite direction 20 toward the receiving end of the table, means for raising the fixed slats at the said receiving end of the table, and means for raising the corresponding ends of the movable slats to said coinciding position relative to the said 25 ends of the fixed slats.
5. A table for receiving flaccid articles transversely of and at one end thereof, said table comprising a series of longitudinally fixed slats, a series of longitudinally movable slats alternating respectively with the said fixed slats, a vertically movable frame to which the corresponding ends of the fixed slats are secured, a horizontally movable frame to which the corresponding ends of the movable slats are secured, and cooperating 30 means on said frames for substantially aligning corresponding edges of the corresponding ends of the two series of slats by coordinated vertical movement of the one frame and horizontal movement of the other frame, and means for lowering the said aligned corresponding ends of the two series of slats in unison while maintained in said aligned relation by the said cooperating means on said 35 frames.
6. A table for receiving flaccid articles transversely of and at one end thereof, said table comprising a series of longitudinally fixed slats, a series of longitudinally movable slats alternating respectively with the said fixed slats, a vertically movable frame to which the corresponding ends of the fixed slats are secured, a horizontally movable frame to which the corresponding ends of the movable slats are secured, cooperating 40 means on said frames for substantially aligning corresponding edges of the corresponding ends of the two series of slats by coordinated vertical movement of the one frame and horizontal movement of the other frame.
7. A table for receiving flaccid articles transversely of and at one end thereof, said table comprising a series of longitudinally fixed slats, a series of longitudinally movable slats alternating respectively with the said fixed slats, a vertically movable frame to which the corresponding ends of the fixed slats are secured, a horizontally movable frame to which the corresponding ends of the movable slats are secured, and an inclined surface on one of said frames arranged to engage an element on the other of said frames for substantially aligning corresponding 45 edges of the said corresponding ends of said fixed and movable slats by coordinated longitudinal movement of the one frame and vertical movement of the other frame.
8. A table for receiving flaccid articles transversely of and at one end thereof, said table comprising a series of longitudinally fixed slats, a series of longitudinally movable slats alternating respectively with the said fixed slats, a vertically movable frame to which the corresponding ends of the fixed slats are secured, a horizontally movable frame to which the corresponding ends of the movable slats are secured, cooperating 50 means on said frames for substantially aligning corresponding edges of the corresponding ends of the two series of slats by coordinated longitudinal movement of the one frame and vertical movement of the other frame arranged to engage and ride on the said inclined rail, for substantially aligning corresponding edges of the corresponding ends of the two series of slats by coordinated longitudinal movement of the one frame and vertical movement of the other frame.
9. A table for receiving flaccid articles transversely of and at one end thereof, said table comprising a series of longitudinally fixed slats, a series of longitudinally movable slats alternating respectively with the said fixed slats, a vertically movable frame to which the corresponding ends of the fixed slats are secured, a horizontally movable frame to which the corresponding ends of the movable slats are secured, cooperating 55 means on said frames for substantially aligning corresponding edges of the corresponding ends of the two series of slats by coordinated vertical movement of the one frame and horizontal movement of the other frame, and means for intermittently lowering the said aligned corresponding ends of the two series of slats simultaneously in successive predetermined steps while maintained in said aligned relation by the said cooperating means on said frames.
10. A table for receiving flaccid articles transversely of and at one end thereof, said table comprising a series of longitudinally fixed slats, a series of longitudinally movable slats alternating respectively with the said fixed slats, a vertically movable frame to which the corresponding ends of the fixed slats are secured, a horizontally movable frame to which the corresponding ends of the movable slats are secured, cooperating 60 means on said frames for substantially aligning corresponding edges of the corresponding ends of the two series of slats by coordinated vertical movement of the one frame and horizontal movement of the other frame.

- tical movement of the one frame and horizontal movement of the other frame, means for intermittently lowering the said aligned corresponding ends of the two series of slats 5 simultaneously in successive predetermined steps while maintained in said aligned relation by the said cooperating means on said frames, means for raising the movable slats to a position above the fixed slats after a predetermined number of said intermittent lowering steps have been effected, and means for 10 moving the movable slats longitudinally of the fixed slats while in said raised position.
11. A table for receiving flaccid articles 15 transversely of and at one end thereof, said table comprising a series of longitudinally fixed slats, a series of longitudinally movable slats alternating respectively with the said fixed slats, a vertically movable frame 20 to which the corresponding ends of the fixed slats are secured, a horizontally movable frame to which the corresponding ends of the movable slats are secured, cooperating means on said frames for substantially aligning 25 corresponding edges of the corresponding ends of the two series of slats by coordinated vertical movement of the one frame and horizontal movement of the other frame, means for intermittently lowering said 30 frames and the said aligned ends of the two series of slats carried by said frames simultaneous in successive predetermined steps from a maximum high to a maximum low position and for reraising the fixed flat frame 35 and the said ends of the fixed slats to the maximum high position subsequent to the two series of slats attaining the said maximum low position, means for raising the movable slat frame and the said ends of the 40 movable slats relative to the said ends of the fixed slats to a position wherein the said ends of the movable slats are elevated above the said ends of the fixed slats when the two series of slats attain said maximum low 45 position, and means for moving the said movable slats and frame longitudinal of and relative to the fixed slats and frame in one direction while elevated with respect to the fixed slats and in an opposite direction as 50 the said ends of the fixed slats and frame are raising, to effect said cooperation of the said cooperating means on the said frames for aligning of the said ends of the slats by said coordinated vertical and longitudinal 55 movements of said frames.
12. The combination of a series of substantially parallel slats, a frame supporting said slats, a second series of slats alternating with the first said series, a frame supporting 60 the second said series of slats, an inclined rail carried by one of said frames, and a rail rider element carried by the other of said frames for leveling the slats of both series with respect to each other upon relative 65 movement between the rail and the rider.

13. The combination of a series of substantially parallel slats, a frame supporting said slats, a second series of slats alternating with the first said series, a frame supporting the second said series of slats, an inclined rail carried by and rigidly secured to one of said frames, and a rail rider element carried by and rigidly secured to the other of said frames for leveling the slats of both series with respect to each other upon relative movement between the frames and the rail and the rider respectively carried thereby. 70

14. The combination of a series of substantially parallel slats, a frame to which corresponding ends of said slats are secured, a second series of slats alternating with the slats of the first series, a frame supporting the second series of slats, an inclined rail secured to the first said frame and projecting longitudinally of the slats, a roller rotatably mounted on the second frame and riding the inclined rail of the first said frame for leveling the slats supported by the frames with respect to each other upon relative longitudinal movement between said frames. 80
